US0D1061321S

(12) **United States Design Patent** (10) **Patent No.:** **US D1,061,321 S**
(45) **Date of Patent:** **** Feb. 11, 2025**

(54) **HYDROPONICS GROWING SYSTEM**

(71) Applicant: **SHENZHEN HOOEBY TECHNOLOGY CO., LTD**, Shenzhen (CN)

(72) Inventor: **Lu Ruan**, Shenzhen (CN)

(**) Term: **15 Years**

(21) Appl. No.: **29/829,110**

(22) Filed: **Mar. 3, 2022**

(30) **Foreign Application Priority Data**

Jan. 13, 2022 (CN) 202230020364.1

(51) **LOC (15) Cl.** **11-02**

(52) **U.S. Cl.**

USPC **D11/144**

(58) **Field of Classification Search**

(57) **CLAIM**

The ornamental design for a hydroponics growing system as shown and described.

DESCRIPTION

FIG. 1 is a perspective view of a hydroponics growing system showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the hydroponics growing system that form no part of the claimed design.

1 Claim, 7 Drawing Sheets
